ADVERTISING DEVICE

Filed Aug. 25, 1931

UNITED STATES PATENT OFFICE

EARL METCALFE, OF CHICAGO, ILLINOIS

ADVERTISING DEVICE

Application filed August 25, 1931. Serial No. 559,301.

This invention relates to an improved previously unknown type of device for advertising wares and merchandise in general through the aid of a store window or similar transparent support.

I have been inspired to accomplish the desired effect and result by utilizing a simple structure employing a new thought in advertising, the principal purpose of the plan being for voluntary selection and effective distribution of advertising circulars, sample merchandise and the like.

The inventive conception further invokes the idea of providing a duplex structure wherein the advertising media accessible to the public is disposed on the exterior of a store window, and wherein the explanatory data and actual products for display purposes are inaccessibly supported on the inner side of said window.

The purpose of the invention is to provide a simple and economical novelty of this class which places the advertising samples and descriptive pamphlets, etc., at a place where passers-by may take one, the actual large sized product being placed in full view but inaccessible from the interior of the window, thus combining the effects of these two primary features in achieving a method of advertising not previously used or covered in the art, so far as I have been able to ascertain.

A particular feature of importance is the idea of placing the two dominating parts of the appliance on opposite sides of the window glass whereby to attract attention of inquisitive persons as to the peculiar systematic arrangement of said parts and using this attraction idea for automatically vending the exteriorly arranged paraphernalia in a unique manner.

In the drawings:

Figure 1 is a perspective view showing that portion of the device supported on the interior of the window.

Figure 2 is a horizontal section through the window showing the inner and outer parts of the structure.

Figure 3 is a vertical sectional view.

The section of the structure supported on

the inner surface of the door window glass 4 is composed of two distinguishable portions; namely, the display rack 5 and the explanatory advertising sign 6. The part 5 is in the nature of an open front box and includes a pair of end walls 7 and 8 joined together by a connective wall 9. The numeral 10 designates a centralized filler of hollow form one purpose of which is to define a pair of end receptacles 11 and 12 to contain the actual articles of merchandise 13. It will be noted that the block-like filler 10 is of such proportions as terminate within the area of the main box 5. This allows the portions of the bottom and walls to project as indicated at the point 13, whereby to define flanges such as serve as abutments to bear against the inner side of the plate glass 4. This provides the desired clearance space to accommodate the suction cups 14 which are attached to the part 10. These suction cups are adapted to fit against the glass 4 in a well known manner. The part 10 also serves as attaching means for the tang portion 15 of the advertising panel or sign 6. On the interior side this sign 6 is formed with printed text matter explanatory of the name, directions, and merits, etc., of the merchandise maintained in the pockets 11 and 12. It is to be observed that the tang portion 15 is sufficiently narrow as not to in any way cover the exposure sides of the said pockets therefore the merchandise is clearly visible from the exterior of the glass 4 when standing on the street. All of the portions of this display rack and sign are made of cardboard or the like with the exception of the suction cups.

The companion part of the structure located on the outer side of the plate glass 4 is in the nature of a pamphlet and sample-containing receptacle 16. This is made up of inner and outer telescopically connected members 17 and 18 respectively cooperating in forming an open front and open top container for circulars and the like (not shown). The walls constituting the part 18 are extended as at point 19 to form abutment flanges which engage the window 4 and which provide the desired clearance for the suction cups 20, these being attached to the

member 17 as seen better in Figure 2. This exterior receptacle 17 is adapted to be placed against the window so that it alines with the tang portion 15 of the sign and the filler 10. 5 Thus it does not obscure any of the advertising data on said sign. Moreover it is further proportioned so as not to conceal or cover the open front portions of the pockets 11 and 12. Thus the merchandise in these 10 pockets is clearly exposed through the window. The advantage in this arrangement is that actual products of merchandise can be placed in the pockets 11 and 12 so that the prospective purchaser may get a dependable 15 idea of the nature of the product advertised by the circulars in the receptacle 16. In some instances, instead of placing circulars in this receptacle 16, I have found it expedient and practical to place small samples of 20 the product therein for public distribution and use. A person viewing this contrivance from a distance obtains the impression that the merchandise is actually supported entirely on the outside of the window. On 25 close observation it is found that the only available material is that contained in the receptacle 16. This unique alined arrangement of the inner and outer companion parts of the structure attracts keen attention on 30 the part of observers and this, it is believed, develops the proper psychological effect for allowing the receptacle 16 to function as an automatic voluntary vending means for the advertising media. 35 It is thought that persons skilled in the art to which the invention relates will be able to obtain a clear understanding of the invention after considering the description in connection with the drawings. Therefore, 40 a more lengthy description is regarded as unnecessary.

Minor changes in shape, size, and rearrangement of details coming within the field of invention claimed may be resorted to in 45 actual practice, if desired.

What is claimed is:

1. An advertising device of the class described comprising a transparent glass support, a sign-equipped merchandise rack supported on the interior of said support, a companion holder disposed on the outer face of said glass support in alinement with a predetermined portion of the rack, said holder being adapted to constitute means for vending samples and advertising literature, pamphlets, and the like.
2. An advertising device of the class described comprising a fixed glass partition, a 60 receptacle supported on the exterior of said glass partition and constructed to accommodate pamphlets, merchandise samples and the like, and means supported on the interior of the window not accessible to passers-by 65 and constructed to serve as a holder for ac-

tual products of the merchandise advertised through the medium of said receptacle.

3. In an advertising ensemble of the class described, an interior section comprising an open front box, a filler in said box constituting a divider and defining an open-front merchandise containing and display pocket, together with an advertising sign for said merchandise including a portion attached to said filler and retaining means in the form of suction cups, an advertising receptacle for exterior use adapted to contain advertising media and having retaining means in the form of suction cups, and a transparent glass plate divider and support interposed 70 between the interior section and said receptacle to permit said parts to be disposed in alinement with each other to possess the requisite advertising relationship, yet permitting only the articles in said receptacle 75 to be accessible from the exterior side of said glass plate.

4. An advertising device comprising a box including a bottom, end walls, and a connecting longitudinal wall, a filler supported in the central portion of said box, the edge portions of the open side of the box projecting beyond the filler to serve as spacing abutments, a sign including an attaching portion secured to said filler, and suction cups 80 secured to the sign and filler.

In testimony whereof I affix my signature.
EARL METCALFE.
